UNITED STATES PATENT OFFICE.

FRANK SCOTT, OF LA FAYETTE, INDIANA, ASSIGNOR TO DUNCAN ELECTRIC MANUFACTURING COMPANY, OF LA FAYETTE, INDIANA, A CORPORATION OF ILLINOIS.

ELECTRICITY METER.

Application filed May 9, 1927. Serial No. 189,947.

My invention relates to electricity meters which are provided with covers held in place by rods carried by the meter bases, these rods projecting forwardly through the 5 covers and having nuts threaded thereon which hold the covers in place. I provide an improved sealing means at the apertures in the covers through which said rods pass. In carrying out my invention, I equip the 10 nuts and covers with engaging male and female portions. To this end I preferably interpose a washer between the inner end of the nut upon each rod that projects through the front wall of the meter cover. The 15 washer and cover desirably have engaging male and female formations as the nut and washer preferably have also, whereby access of tampering wires to the rotating element of the meter enclosed by the cover for checking or stopping the meter is effectively guarded against.

I will explain my invention more fully by reference to the accompanying drawing in which Fig. 1 is a sectional view of one construction; Fig. 2 is an enlargement of a part of the structure as it appears in Fig. 1; Fig. 3 is a perspective view of parts shown in Fig. 2, but in separated relation; and Fig. 4 is a sectional view of another construction, 30 which is preferred.

The meter base in the meter shown is inclusive of a plate 1 formed with a forwardly projecting wall 2 to constitute a chamber. The motive element of the meter is suitably 35 mounted upon the rear of a partition wall 3. The electro-magnets of the motive element of the meter, of which the current magnet 4 is shown, are upon the rear side of the wall 3, being surrounded by the wall 2 and enclosed within the chamber defined by said wall. The upright meter spindle 5 is positioned by bearings which are carried by the wall 3 upon the front thereof, as is understood by those familiar with the art. The 40 spindle carries a non-magnetic metallic armature disc 6 which extends into inductive relation with the magnets.

The cover 7, commonly of glass, is seated upon the front portion of the wall 2, a sealing gasket 8 being interposed between the cover and said wall. The cover is held in 50 position by two rods 9 which are carried by the base and project forwardly therefrom

through the cover. Two nuts 10 are threaded upon these rods and press upon the 55 cover to hold it upon its seat.

A washer is employed between each nut and the front of the cover. Each washer has a body portion 11 which is directly engaged by the inner face of the correspond- 60 ing nut. The cover and each washer have engaging male and female formations as do each washer and nut. In the preferred embodiment of the invention the cover is formed with a boss 12 surrounding each 65 opening through which a rod 9 passes and each washer is formed with a skirt portion 13 extending toward the cover and receiving the corresponding boss. Each washer also has a sleeve continuation 14 extending away 70 from the cover and through which the corresponding rod 9 passes. The inner end of the bore of the corresponding nut is enlarged as indicated at 15, and receives the correspond- 75 ing sleeve 14 that is preferably in sliding relation with the nut. The structure of Fig. 4 is obvious. In this structure, a felt washer 16 is also shown.

It is obviously extremely difficult, if not impossible, to fish a wire through the front 80 of the cover into braking contact with the rotating element of the meter.

Changes may be made without departing from the invention.

Having thus described my invention, I 85 claim:

1. The combination with an electricity meter; of a supporting base therefore; a cover for the meter and engaging said base; a rod projecting from the base and passing 90 through an opening formed in the cover; a sealing nut screwed upon the outer end of said rod; and a washer interposed between the nut and cover and having a skirt portion extending toward the cover and receiving a 95 boss that is formed on said cover around said opening, said washer also having a sleeve continuation extending away from said cover and through which said rod passes, the inner end of the bore of the nut being enlarged and receiving said sleeve upon the washer.

2. The combination with an electricity meter; of a supporting base therefor; a cover for the meter and engaging said base; a rod projecting from the base and passing 105

- through an opening formed in the cover; a sealing nut screwed upon the outer end of said rod; and a washer interposed between the nut and cover and having a sleeve continuation extending away from said cover and through which the rod passes, the inner end of the bore of the nut being enlarged and receiving said sleeve upon the washer.
- 5 3. The combination with an electricity meter; of a supporting base therefor; a cover for the meter and engaging said base; a rod projecting from the base and passing through an opening formed in the cover; a sealing nut screwed upon the outer end of said rod; and a washer interposed between the nut and cover and having a skirt portion extending toward the cover and receiving a boss that is formed on said cover 10 around said opening.
- 15 4. The combination with an electricity meter; of a supporting base therefor; a cover for the meter and engaging said base; a rod projecting from the base and passing through an opening formed in the cover; a sealing nut screwed upon the outer end of said rod; and a washer interposed between the nut and cover, said cover and washer 20 having engaging male and female formations surrounding said opening, said washer and nut also having engaging male and female formations surrounding said rod.
- 25 5. The combination with an electricity meter; of a supporting base therefor; a cover for the meter and engaging said base; a rod projecting from the base and passing through an opening formed in the cover; a sealing nut screwed upon the outer end of said rod; and a washer interposed between the nut and cover and having a sleeve 30 continuation extending away from said cover and through which the rod passes, the inner end of the bore of the nut being enlarged and receiving said sleeve upon the washer.
- 35 6. The combination with an electricity meter; of a supporting base therefor; a cover for the meter and engaging said base; a rod projecting from the base and passing through an opening formed in the cover; a sealing nut screwed upon the outer end of said rod; and a washer interposed between the nut and cover, said nut and washer having engaging male and female formations surrounding said rod.
- 40 7. The combination with an electricity meter; of a supporting base therefor; a cover for the meter and engaging said base; a rod projecting from the base and passing through an opening formed in the cover; a sealing nut screwed upon the outer end of said rod, said cover having a boss surrounding the opening through which said rod passes; and a skirted member between said nut and cover and surrounding said boss.

In witness whereof, I hereunto subscribe my name.

FRANK SCOTT.
